ANTENNA

Application filed June 9, 1930, Serial No. 459,863, and in Germany June 11, 1929.

Particularly with a view to obviate fading, it is important that the antennæ radiating electromagnetic waves; for instance, for broadcast purposes, should exhibit as little 5 radiation in an upward direction as feasible. According to the present invention this end is attained by forming the antenna in the form of a complex radiator or system wherein a plurality of auxiliary radiators is disposed around a central radiator, the said auxiliary radiators forming a closed curve or 10 loop, e. g., a circle.

In the accompanying drawing, Figure 1 illustrates an antenna system embodying the principles of my invention, and

Figure 2 is given by way of explanation thereof.

One embodiment of the basic idea of the

distribution for the Poynting vector (radiation vector of electromagnetic energy). It is found, for instance, for the system illustrated in Figure 1 that the value S of the Poynting vector for any given point whose azimuth angle with the vertical plane is given by the line AB , Figure 1, and whose zenith angle (angle between the vertical plane and the connecting line of the point in question and the center a of the antenna system) there holds goods the following equation:

$$S = C \frac{\cos^2 \left(\frac{\pi}{2} \cos \theta \right)}{\sin^2 \theta} [(1 + \alpha \phi \cos \psi)^2 + (\alpha \phi \sin \psi)^2] \quad 60$$

where C a constant, while ϕ is given by this formula:

$$\phi = \cos \left(\frac{2\pi d}{\lambda} \sin \theta \cos \psi \right) + \cos \left(\frac{2\pi d}{\lambda} \sin \theta \sin \psi \right) + \cos \left[\frac{2\pi d}{\lambda} \sin \theta \sin \left(\psi + \frac{\pi}{4} \right) \right] + \cos \left[\frac{2\pi d}{\lambda} \sin \theta \sin \left(\psi - \frac{\pi}{4} \right) \right] \quad 65$$

invention is diagrammatically illustrated in Figure 1. In this arrangement the radiator system comprises a vertical centrally disposed antenna a having a length of $\lambda/4$ in 30 which there flows a current J_0 , and eight vertical antennæ b of about the same height and forming around the central antenna a circle of a radius of $\lambda/4$. The auxiliary radiators are fed with currents

$$\frac{J_0}{8}$$

presenting a phase displacement angle of 180 degrees in relation to the current of the 40 central radiator.

Presupposing a ground of perfect conductivity and sinusoidal current distribution in the various antennæ it is possible by the superposition of the space radiation fields 45 of all of the radiators to calculate the space

d is the radius of the circle and α the ratio

$$\frac{J_1}{J_0}$$

of 2 times the current J_1 in the outer antenna and the current J_0 in the inner antenna.

For any direction characterized by θ and ψ it is possible to determine by the aid of the above formula the radiation amplitude in a definite unit distance.

The manner in which the above mathematical expression for radiation characteristic is obtained is derived below.

In the example cited 8 radiators are uniformly and regularly arranged around a circle having a radius d . All of these are excited under co-phasic conditions, and an additional radiator is located centrally. All of

the aerials are of quarter wave length. The radiators are above a ground or soil possessing infinitely high conductivity, and this is duly considered by the addition of the image.

5. Using as a basis rectangular coordinates x, y, z , or spherical polar coordinates r, φ and θ respectively, between which there is to hold good the relation

10 $x = r \sin \theta \cos \varphi, y = r \sin \theta \sin \varphi, z = r \cos \theta$ there results for the mean time-value of the Poynting vector S expressed by a complex formula

$$15 S = N \left\{ C \sin \theta \int_{-\frac{\lambda}{4}}^{\frac{\lambda}{4}} \cos k z_0 e^{ikz_0} dz_0 \sum A_s e^{ik} \left(\frac{xx_s}{r} + \frac{yy_s}{r} \right) + i\psi_s \right\} \quad 80$$

20 where x_s and y_s are the coordinates of the base of the sth radiator, A_s the current amplitude, and ψ_s the phase of the sth radiator. C is a constant. N denotes the "operator-norm", i. e., the formation of the absolute value of the following expression, further

$$25 k = \frac{2\pi}{\lambda} \quad 90$$

(where λ = wave length) and

$$30 i = \sqrt{-1} \quad 95$$

In the special case where 8 radiators are uniformly disposed around a circle of radius d , all of which are excited under cophasic condition and with the same amplitude A_1 and where a central radiator is mounted 35 whose amplitude shall be assumed to be equal to A_0 there is obtained from the above formula if the coordinate origin of the central radiator is fixed, while the base coordinates of the other radiators

$$40 d, 0; \frac{d\sqrt{2}}{2}, \frac{d\sqrt{2}}{2}; 0, d; \frac{-d\sqrt{2}}{2}, \frac{d\sqrt{2}}{2}; -d, 0; \\ \frac{-d\sqrt{2}}{2}, \frac{-d\sqrt{2}}{2}; 0, -d; \frac{d\sqrt{2}}{2}, \frac{-d\sqrt{2}}{2} \quad 105$$

45 then

$$50 S = N \left\{ C \frac{\cos \left(\frac{\pi}{2} \cos \psi \right)}{\sin \theta} \left[A_0 + A_1 e^{i\psi} \left(e^{ikd \frac{x}{r}} + e^{-ikd \frac{x}{r}} + e^{ikd \frac{y}{r}} + e^{-ikd \frac{y}{r}} + e^{ikd \frac{\sqrt{2}x+y}{r}} + e^{ikd \frac{\sqrt{2}x-y}{r}} + e^{-ikd \frac{\sqrt{2}x+y}{r}} + e^{-ikd \frac{\sqrt{2}x-y}{r}} \right) \right] \right\} \quad 115$$

55 ψ denotes the phase displacement angle between the peripheral radiators and the central radiator, from which one gets the following equation:

$$60 S = N \left\{ C \frac{\cos \left(\frac{\pi}{2} \cos \theta \right)}{\sin \theta} \left[A_0 + 2A_1 e^{i\psi} \left(\cos (kd \sin \theta \cos \phi) + \sin \cos (kd \theta \sin \phi) + \cos \left(kd \sin \theta \sin \left(\phi + \frac{\pi}{4} \right) \right) + \cos \left(kd \sin \theta \sin \left(\phi - \frac{\pi}{4} \right) \right) \right) \right] \right\} \quad 125$$

65

Introducing for the sake of brevity

$$\phi = (\cos (kd \sin \theta \cos \phi) + \cos (kd \sin \theta \sin \phi) + \cos \left(kd \sin \theta \sin \left(\phi + \frac{\pi}{4} \right) \right) + \cos \left(kd \sin \theta \sin \left(\phi - \frac{\pi}{4} \right) \right)) \quad 70$$

then

$$75 S = C \left(\frac{\cos \left(\frac{\pi}{2} \cos \theta \right)}{\sin \theta} \right)^2 (A_0^2 + 4A_1^2 \phi + 4A_0 A_1 \phi \cos \psi) \quad 130$$

or

$$85 S = C'' \left(\frac{\cos \left(\frac{\pi}{2} \cos \theta \right)}{\sin \theta} \right)^2 [(1 + \alpha \phi \cos \psi)^2 + (\alpha \phi \sin \psi)^2] \quad 90$$

if for simplicity's sake there has been introduced therein

$$95 \alpha = \frac{2A_1}{A_0} \quad 135$$

For further details respecting derivation of the expression reference must be made to article published in Telefunkenzeitung No. 53, December 1929 "Calculation of radiation diagram of aerial combinations."

What follows therefrom is that the azimuth diagram is nearly a circle so that this antenna system is suited for broadcast work. Plotting furthermore a polar diagram for a meridian plane, say, the vertical plane 105 through the line AB, Figure 1, there results curve I, Figure 2. For the sake of comparison there is also shown in Figure 2 the radiation diagram II which holds true of the case where only the radiator a is provided. It 110 will be noted that if conditions are so chosen

that the horizontal radiations are equal to each other in both cases, undesired upward radiation is considerably greater when the central antenna a alone is present than when

120 a system as shown in Figure 1 is employed. 130

The disposition of auxiliary radiating antennæ as above described along a circular line results substantially in an equal distribution of the radiations for all horizontal directions. If another distribution is wanted then the auxiliary radiators may be mounted along a different curve or line, and it is not necessary that this curve should be symmetrical. No matter what the superposition of the radiations of each antenna or radiator, it is possible to calculate the distribution of the Poynting vector for the desired position of the auxiliary radiators as a function of the amplitudes and phases of their currents, and one may then choose those phases and amplitudes of the currents for the various auxiliary antennæ which will result in an optimum distribution of the radiations. However, it would be simpler in this instance to proceed empirically in that for extremely short (ultra-short) waves, say, of an order of 50 centimeters, a conveniently reduced antenna model is erected and by that the most favorable amplitudes and phases of the various radiators are ascertained from field intensity measurements.

Also the number of the auxiliary antennæ may be chosen differently. It is even feasible to operate the auxiliary radiators without supplying them with energy, in other words, to use them as mere reflectors.

We claim:

1. An antenna system adapted to radiate substantially uniformly in all directions in a horizontal plane comprising a centrally disposed vertical antenna and a plurality of outer vertical antennæ located on a circle around said centrally disposed antenna, of a radius equal to one quarter of the communication wave, all of said antennæ having a length substantially equal to one quarter of the communication wave, said outer antennæ being fed with currents presenting phase displacement angles of 180 degrees with respect to the current in the central antenna.

2. A system in accordance with claim 1 having eight outer antennæ disposed around said central antenna.
